UNITED STATES PATENT OFFICE

JOHN STOCKER, OF SEDWARD, NEBRASKA

ROAD MAINTAINER

Application filed November 30, 1928. Serial No. 322,633.

This invention relates to a road maintainer and has for its objects, broadly, to provide a maintainer which will consist of few and simple parts so that it may be manufactured at a limited expense and will be convenient and durable in use.

One of the objects of the invention is to provide such an arrangement of blades for the frame that the loose earth or hummocks on the surface will be moved transversely as well as forwardly of a road bed for filling the pockets or depressions so that the road bed will be smooth.

Another object is to provide a main scraper-blade which may be adjusted to various angles relative to the rectangular frame of the maintainer for co-operation with the first named blades.

Another object is to provide a maintainer having only two wheels so that it may be conveniently "turned about" within a limited space.

Another object is to provide such a mounting for the wheels that the blades at one side of the maintainer will cut deeper into the earth than at the opposite side of the maintainer for conducting earth from ditches or gutters toward the middle of a road bed.

The invention includes an adjusting-frame arranged to swing from the frame of the maintainer together with mechanism on said adjusting-frame for adjusting all of the scraper-blades to permit them to enter or lie closely to the ground as may be required, and includes clamping means for the main scraper-blade found to be of great advantage for rigidly securing it to the frame of the maintainer, to permit adjustments thereon and removal therefrom.

With the foregoing objects in view and others to be mentioned, the invention presents a new and useful construction, combination and arrangement of parts as described and claimed, and as illustrated in the accompanying drawings, it being understood that changes in form, size, proportion of parts and minor details may be made as found to be of advantage, said changes be-

ing within the scope of the invention as claimed.

In the drawings Fig. 1 is a plan view of a road maintainer embodying my invention. Fig. 2 is a view of the same in side elevation. Fig. 3 is a plan view showing a part of the rectangular frame of the maintainer, a part of a scraper-blade and a clamping device mounted thereon. Fig. 4 is a side view of the clamping device, the scraper-blade being in transverse section. Fig. 5 is a perspective view showing the crank-shafts, wheels mounted thereon, and a part of the frame for the maintainer. Fig. 6 is a rear view of the maintainer. Fig. 7 is a perspective view showing a part of the adjusting-frame and mechanism thereon, a part of a V-shaped scraper and part of the frame of the container.

Referring now to the drawings for a more particular description, numeral 8 indicates a rigid rectangular frame for the maintainer, its rear end being supported by a pair of wheels 9, the front part of the frame being supported by an adjusting-frame 10 adapted to be connected with a tractor (not shown) or other vehicle by a draw-bar 11, the front end of the frame 10 being provided with a coupling-plate 12 to which one end of the draw-bar may be attached. The opposite end of the draw-bar may be connected with the tractor by any suitable means, a pin 13, as best shown in Fig. 2 of the drawings, being shown for this purpose.

Numeral 14 indicates an upright supporting-frame which projects above and is suitably secured to the front end of the frame 8, its function being to operate as a support for the adjusting-frame 10.

The frame 10 consists of a pair of arms or bars 15 pivotally mounted at 16 upon the sides of the frame 8, said bars projecting forwardly-convergent through the frame 14 as shown in Figs. 1 and 7 of the drawings for a mounting of their front ends upon the plate 12.

As shown in Figs. 2 and 7 of the drawings, the bars 15 are of angular form and each has a part α of greater elevation disposed beneath the top of the upright frame

14. In other words these bars have an upward inclination from their pivotal mounting 16 to the supporting-frame 14 and a downward inclination from the frame 14 to the coupling-plate 12.

5 The adjusting-frame thus described and mechanism thereon are for the purpose of elevating or lowering the rectangular frame 8 and scraper-blades relative to the road bed. 10 By use of its parts to be described the road maintainer may be drawn by a tractor or vehicle with its rectangular frame and scraper-blades disposed at a suitable elevation so that the entire weight of the maintainer will be supported by the wheels 9 15 and draw-bar 11, this being a matter of convenience when moving it over concrete pavements or from one locality to another or over roads not to be operated upon, and 20 said frame 10 is depended upon for permitting the scraper-blades to enter the ground or at least to maintain the scraper-blades at a suitable elevation for cutting the hummocks and rough or uneven surfaces 25 and filling the depressions or pockets of a road bed. Also the mechanism on the frame 10 are depended upon for rotating one or both crank shafts 17.

It will be understood that when the draw-bar 11 is secured to the coupling-plate 12 by the pair of keepers *a* and *b* shown in Fig. 2 of the drawings, said draw-bar will provide a support for the front end of the frame 10, and when the pin 13 connects the 30 draw-bar to a tractor said tractor will operate as a support for the adjusting-frame 10.

The mechanism which is mounted on the adjusting-frame is very simple and of inexpensive construction. It provides means for 40 elevating and lowering the front part of the frame and scraper-blades relative to the frame 10 and more particularly with reference to the draw-bar 11 and pin 13. Also, as will be seen, it provides means for 45 rotating the crank-shafts 17 for elevating or lowering the rear part of the frame 8 and scraper-blades best shown in Fig. 7 of the drawings.

Numerals 18 indicates a shaft, upon which 50 is mounted a worm-wheel 19 and a drum 20, said shaft having bearings in a pair of upright brackets 21 which are secured to a cross-plate 22, the latter being mounted on the pair of bars 15 of the adjusting-frame 55 10.

At 23 is indicated an operating-shaft in suitable bearings, provided with a worm 24 in engagement with the wheel 19 and provided with a hand-wheel 25.

60 Each crank-shaft 17 is disposed on the rear end of the frame 8 in suitable bearings and provides a bearing for a wheel 9, and is provided at its inner end with a handle-bar or lever 26.

Numerals 27 indicates a flexible strand or

cable adapted to be wound upon the drum 20 when the operating-shaft 23 is rotated, and any suitable connection may be made for the cable 27 with the handle-bars 26 or either of said handle-bars for rotating the 70 crank-shafts by rotating the drum 20, the preferred parts for these connections to now be described.

Numerals 28 indicates an attenuated pull-rod which is disposed above the maintainer, 75 its front end preferably being provided with a chain 29 having a hook 30 adapted to engage the loop 31 of the cable 27. Numerals 32 (Figs. 1-2) indicate a pair of chains of different lengths which are secured to the rear end of the rod 28. Each handle-bar 26 is preferably provided near its outer end with a chain-holder 33, and it will be understood that the chain 29 may be disposed with one of its links engaging the hook 30, 80 and that the end-portions of the chain 32 may be secured to the holders 33 of the levers or handle-bars 26.

In operation, if the drum is rotated in one direction, the levers 26 will be swung forwardly for elevating the frame 8 and scraper-blades from the ground, their weight being supported by the wheels and the tractor as mentioned, and a rotation of the drum in an opposite direction will permit the 90 frame 8 and scraper-blades to move downwardly so that said blades will engage the ground.

As is obvious, the scraper-blades which are rigidly secured to the frame 8 may be 100 maintained in an elevated or lowered position.

As best shown in Fig. 5 of the drawings, each chain-holder 33 is provided with a slot *c* which opens upon an eye *d* so that when 105 one of the end-portions of the chain 32 is moved through an eye *d* one of the links may become caught in the slot *c*, and since each crank-shaft is free to rotate independently of the other crank-shaft adjustments 110 may be made to permit the frame 8 and scraper-blades to be disposed inclinedly, this inclination being transverse and approximately at right-angles to the longitudinal axis of the maintainer, this feature 115 being of advantage in forming the transversely curved surface of the road bed, generally required for highways, and it will be seen that, by use of the parts as described, the degree of transverse inclination for the frame 8 and scraper-blades may be greater 120 or lesser as may be required.

It will be understood that if the distance between a lever 26 and the end of the strand 125 28 is increased or decreased, the arcs of movement of the crank-shafts will be changed during operation. While I have shown chains 32 for connecting the levers with the end of the strand 28 and prefer their use, any flexible members may be em- 130

ployed and they may be arranged in any suitable manner for maintaining each lever at a selected distance from the end of the strand 28.

5 Means are provided for elevating the adjusting-frame 10 so that its front end may be swung upwardly for securing it to the tractor. For this purpose the hook 30 is first released from the loop 31 and the cable 10 27 is then used, its loop 31 being placed in engagement with a hook 34 which is mounted on the upper part of the supporting-frame 14, and as described it is obvious that, if the drum is rotated in one direction, 15 the front end of the frame 10 may be elevated. This feature is often a matter of convenience since the adjusting-frame is comparatively heavy, but may be readily lifted by use of the operating-shaft 28.

20 The position of the cable 27 during this last named operation is shown by dotted lines in Fig. 7 of the drawings.

The frame 10 is provided with a holder-plate 35 provided with a pair of slots opening on its upper edge, and at 36, by broken lines, is indicated a short chain which is secured at its lower end to the frame of the 25 maintainer and is adapted to be disposed with one of its links engaging in one of the 30 slots of said holder-plate, the result being that the frame of the maintainer will be prevented from moving downward from the adjusting-frame 10 while the latter is supported, this feature being useful in some 35 instances.

It will be understood that the loose part or end-portion *e* of the chain 29, shown in Fig. 7 of the drawings, may be disposed with one of its links engaging in one of the 40 slots of the holder-plate 35 before the hook 30 is disengaged from the loop 31 of the cable 27 to prevent any swinging movement of the levers 26 or rotatable movements of the crank-shafts 17.

45 Numeral 37 indicates, by broken lines, a short chain which may be mounted on a hook 38 which is secured to the maintainer frame and this chain, after it has been mounted on said hook, is adapted to be disposed with one of its links engaging in one of the 50 slots of the holder-plate 35 for supporting the frame 1 above the ground after the front end of the frame 10 has been connected with the tractor.

55 This second short chain 37 is shown in Fig. 7 of the drawings in dotted lines, and since one of its links may engage in a slot of the holder-plate 35 somewhat remote from the slot engaged by the chain 36 the 60 maintainer frame may be adequately supported by the adjusting-frame 10 and transverse swinging movements of frame 8 avoided.

While I have mentioned cables and 65 chains in describing the invention I do not

wish to be limited in this respect and I may employ various kinds of strands or flexible members as a substitute therefor, and the pull-rod 28 may consist of a cable or flexible strand if desired.

70 I provide a V-shaped scraper consisting of a pair of rearwardly-divergent blades 39, said scraper being disposed in a plane beneath the frame 1 and rigidly secured thereto, and in operation these blades will cut down hummocks and raised portions of a road bed, will conduct loose earth outwardly as well as forwardly of the forward line of movement of the maintainer, and since the end-portions of these blades project beyond the sides of the frame 8, some of the loose earth may be carried to the ends of said blades.

75 Numerals 40 indicate a pair of scraper-blades each provided with a brace 41 suitably secured to the frame 8 and suitably secured to said blades. The blades 40 are preferably disposed in the plane of the blades 39 beneath the frame 8 and are secured to said frame midway between their ends, and their rear ends are secured to a cross frame-plate 42.

80 Each scraper-blade 40 is disposed approximately at right-angles to a blade 39 adjacent thereto, and since its outer end is disposed outwardly of the frame 8 beyond the end of a blade 39, all loose earth which may be moved beyond the end of a blade 39 will be caught by a blade 40 and conducted toward the middle of the frame 8.

85 Numeral 43 indicates a main scraper-blade having a length greater than the width of the frame 8, and is removably mounted thereon so that, when thus mounted it may be disposed at right-angles to said frame or at selected degrees of inclination, and in 90 operation the pockets in a road bed will become filled and the surface rendered smooth. The loose earth carried inwardly of the frame 8 by action of the pair of scraper-blades 40 during the forward movement of the maintainer, will be delivered to the scraper-blade 43, and obviously, if this blade is disposed inclinedly to the forward movement of the maintainer frame, 95 any loose earth not deposited in the pockets or depressions may be conducted toward the middle or sides of a road bed.

100 Since the blade 43 may require change of position it is important that means should be provided for a convenient mounting on the sides of frame 8.

105 For this purpose I provide a particular clamping device best shown in Figs. 3 and 4 of the drawings, and consisting of an adjusting-bar 44 adapted to lie above and across the frame 8 and a pair of hook-arms 45 carried by the bar 44 adapted to engage the flanges of said scraper-blade, a crank-arm 46 threaded in the adjusting-bar being 110

rotatable for pressing the scraper-blade and its flanges against the bottom of the frame, locking-bars 47 also being employed.

This clamping device has been found to be very effective in firmly securing the scraper-blades to the sides of the frame, and permits the blade to be shifted to desired inclinations conveniently and without undue loss of time.

10 On account of the arrangement of the scraper-blades it will be appreciated that a road bed will be subjected to three treatments while the maintainer is moving forwardly, the loose earth being moved forwardly and outwardly by the V-shaped scraper, and moved forwardly and inwardly of the frame by the pair of blades 40 and finally the earth will be treated, as mentioned, by the blade 43, all of these blades 20 being assembled, comparatively, in a limited area.

By referring to Fig. 7 of the drawings it will be seen that the loop 31 may engage the hook 38, and the drum may then be rotated for elevating the frame 8, or rear part thereof, to any suitable height. The chain 37 may then be disposed with one of its links engaging in a slot of the plate 35 with its end secured to the hook 38 for maintaining frame 8, at the suitable height mentioned, and thereafter the loop 31 may be placed in engagement with the chain-hook 30.

I claim as my invention:—

35 1. In a road maintainer arranged to be drawn by a tractor, a maintainer-frame, scraper-blades below and secured to said frame, an adjusting-frame mounted upon and extending forwardly of the maintainer-frame for a coupling with said tractor, a pair of crank-shafts each provided with a lever and having bearings on the maintainer-frame, wheels on the crank-shafts, a drum having bearings on the adjusting-frame, and 40 a strand mounted on the drum and connected with the levers of the crank-shafts, said drum being rotatable for moving the crank-shafts in a circle's arc for elevating or 45 lowering said maintainer-frame and scraper-blades.

50 2. In a road maintainer, a rectangular frame, a scraper-blade disposed transversely of the frame below the sides thereof, an adjusting-bar above the frame, a pair of 55 hook-bars carried by the adjusting-bar for engaging the flanges of the frame, locking-bars carried by the scraper-blade each engaging a hook-bar, and a crank-arm threaded in the adjusting-bar, and adapted to be 60 rotated for pressing the scraper-blade against said frame.

65 3. In a road maintainer arranged to be drawn by a vehicle, a maintainer frame having a part adapted to be connected with the vehicle, scraper-blades below and carried by

said frame, a pair of crank-shafts each mounted on the frame and provided with a lever, wheels mounted on the crank-shafts, a rotatable drum carried by said frame, a strand mounted on the drum and provided with a pair of terminal flexible members for mountings on said levers, one of the flexible members of said pair having a length greater than the length of the other member for causing one of the levers of a 70 crank-shaft to move in a circle's arc greater than the arc of movement of the other crank-shaft for elevating a part of the maintainer frame when said drum is rotated.

In testimony whereof, I have affixed my 75 signature.

JOHN STOCKER.
